UNITED STATES PATENT OFFICE

99,940

DESIGN FOR A CONE CAKE BAKER

Tofick Hallak, Kansas City, Mo.

Application November 4, 1935, Serial No. 59,365

Term of patent 7 years

To all whom it may concern:

Be it known that I, Tofick Hallak, a citizen of the United States of America, residing at Kansas City, Jackson County, Missouri, have invented a new, original, and ornamental Design for a Cone Cake Baker, of which the following is a specification, reference being had to the accompanying drawing, forming a part thereof,

In the drawing:—

I claim:—

The ornamental design for a cone cake baker, as shown,

TOFICK HALLAK,
